UNITED STATES PATENT OFFICE

111,960

DESIGN FOR A MIRROR

Ceabern S. De Rauf, Des Moines, Iowa

Application September 23, 1937, Serial No. 71,757

Term of patent 3½ years

To all whom it may concern:

Be it known that I, Ceabern S. De Rauf, a citizen of the United States, residing in Des Moines, Polk County, Iowa, have invented a new, original, and ornamental Design for a Mirror, of which the following is a specification, reference being had to the accompanying drawing, forming a part thereof.

Fig. 1 is a front view of my mirror showing my new design.

Fig. 2 is a top plan view of my mirror.

I claim:

The ornamental design for a mirror, substantially as shown.

CEABERN S. DE RAUF.
